Attorney

UNITED STATES PATENT OFFICE

ALEXANDER HERMAN, OF BERLIN, GERMANY

WINDOW

Application filed October 21, 1930, Serial No. 490,275, and in Germany September 25, 1929.

My invention relates to windows, and more particularly to windows having metal sashes.

It is an object of my invention to provide a window of the type referred to which is readily manufactured at low cost and particularly is without the normal expensive and difficultly machined sectioned sashes.

To this end I make the sash of flat inclined metal bars.

A sash of this type affords a good seat for the pane on the inclined inner faces of the bars without necessitating sections, prevents extraction of the pane from one side, generally the outside of the window, and is braced by the pane so that forces acting on the sash are uniformly distributed through the pane. The inclined outer faces of the sash make an excellent fit on the window frame which is tight against any weather without packing strips and other complicated accessories.

Any number of panes may be inserted in a sash by securing within a principal or outer sash any number of inner sashes, each holding a pane and adapted to be rocked separately about the sash pin. Obviously the complete window may also be rocked about the pin. A double or multiple window of this kind is very simple and cheap.

The frame for lining the window opening may be designed in various ways. For instance, I may provide an angle section and fill it with means for holding tight at the faces of the sash, or I may insert a sectioned fillet in the opening, and in the fillet I may insert a frame of flat bars like the sash.

In the accompanying drawing several windows embodying my invention are illustrated in section by way of example.

In the drawing

Fig. 1 shows a window with a frame of angle section.

Fig. 2 is a perspective illustration of a sash,

Fig. 3 shows a window with a frame consisting of a fillet and flat bars like the sash, and

Fig. 4 shows a window having two sashes, each with a pane.

Referring now to the drawing, and first

to Fig. 1, *a* is a wall, its outside being at the left, *b* is an angle section inserted in the opening as a frame, with its vertical flange at the outside, and *c* is a packing within the section which may be rubber, felt, or the like, and may be subdivided into layers or strips.

In windows opening to the outside the vertical flange will obviously be on the inside, that is, at the right in Fig. 1.

Referring now to Fig. 2, the sash *r* is built up from flat and inclined metal bars, one of which is shown in section at *d* in Fig. 1. *e* is the pane which is inserted in the sash simply by pushing it toward the outside, without any means for holding it on the outside as the inclination of the sash bars holds it in a definite position. Obviously the pane cannot be extracted from the outside. Preferably a strip of putty is placed against the outside of the pane at *f*, not for holding it but for making a tight fit. *b* is a fillet, preferably of wood, on the inside of the pane *e* which is held by a screw, or screws, *g*. *p* is the sash pin.

Referring now to Fig. 3, the sash, with its bars *h*, the pane *e* and the putty strip *f*, is designed as described but equipped with a flat fillet *g*, which admits more light. *k* is a fillet of triangular section which may be of wood, is inserted in the opening of the window in the same position as the angle section in Fig. 1, and is lined with a frame *i* which corresponds to the outside of the sash *h*.

In combination with this type, a strip, not shown, of packing material may be secured to the outside of the sash, and, if desired, the packing *c*, Fig. 1, may also be secured to the sash on the outside. It is only important that the sash should be packed along inclined faces as the sash exerts a sort of wedge action on the packing which effects a tight fit without seizing so that it opens readily notwithstanding its tight fitting.

Referring now to Fig. 4, the angle-section frame *b* is inserted in the opening of the wall *a* as described with reference to Fig. 1 but obviously a fillet such as *k*, Fig. 3, might also be provided as the frame. *m* and *n* are two sashes, with panes *e*₁ and *e*₂, respectively, which are mounted to rock on the same pin.

p, the inner sash *n* fitting the outer sash *m*. Both sashes are designed as shown in Fig. 2, and the outer sash *m* makes a tight fit on the packing in the section *b* which packing is not shown in Fig. 4 but obviously may be the same as the packing *c* in Fig. 1. The pane *e*₁ is held in its sash *m* by a fillet *q*, the same as in Fig. 1, and is held tight by a strip of putty *f* while the pane *e*₂ is inserted between two fillets *o* and *o*₁. The inner sash *n* may be opened independently of the outer sash *m*, or both sashes may be opened together.

The edges of the panes *e* etc. are preferably beveled as shown in Figs. 1 and 4 so as to make a better fit with the inner faces of their sashes but the edges may also be parallel, as shown in Fig. 3.

The fillets *g*, *o*, *o*₁, and *q*, may be so designed as to conceal the sash and to make up a good-looking frame at right angles to the panes.

Any number of windows may be arranged in juxtaposed or superimposed relation in the manner indicated in Fig. 4, without necessitating cross frames and the like. All windows, whatever their number, may be mounted to rock about a single pin.

The sash, or sashes, are almost invisible from the outside, and may be completely concealed if desired for esthetic reasons.

I claim:

1. In a window frame construction a sash of flat inclined metal bars.
2. A window comprising a sash of flat inclined metal bars, a pane inserted in said sash, and means for holding said pane.
3. A window comprising a sash of flat inclined metal bars, a pane inserted in said sash, the edges of said pane being beveled so as to cooperate with said bars, and means for holding said pane in place in said sash.
4. A multiple window comprising a plurality of sashes of flat inclined metal bars, the inside of one sash fitting the outside of the other.
5. A multiple window comprising a plurality of sashes of flat inclined metal bars, the inside of one sash fitting the outside of the other, and a pin about which the sashes are mounted to rock.
6. A window comprising a sash of flat inclined metal bars, and a frame adapted to be inserted in a window opening said frame being provided with inner faces to abut and fit said sash.
7. A window comprising a sash of flat inclined metal bars, and a frame adapted to be inserted in a window opening said frame including a fillet, and a frame of flat metal bars on said fillet for fitting said sash.
8. A window comprising a sash of flat inclined metal bars, a frame of angular section adapted to be inserted in a window opening, and packing means in said frame fitting said sash.

9. A double window comprising two sashes of flat inclined metal bars, a sash pin about which both sashes are mounted to rock, the inner sash being shorter than, and fitting in, the outer sash, and adapted to be moved independently of said outer sash, and a pane in each sash.

10. A window comprising a sash of flat metal bars, a pane inserted in said sash, and fillets formed with inclined faces fitting said sash on the inside, said fillets being formed with faces at right angles to said pane at their free sides, so as to make up a continuous frame at right angles to said pane within said sash for holding said pane in said sash.

In testimony whereof I affixed my signature.

ALEXANDER HERMAN.
